UNITED STATES PATENT OFFICE.

JAMES LIVINGSTON AND JOHN KENNEDY, OF TORONTO, ONTARIO, CANADA.

RELIEF-VALVE FOR ENGINES.

SPECIFICATION forming part of Letters Patent No. 269,301, dated December 19, 1882.

Application filed August 10, 1882. (No model.)

To all whom it may concern:

Be it known that we, JAMES LIVINGSTON and JOHN KENNEDY, both subjects of the Queen of Great Britain, residing at the city 5 of Toronto, in the county of York, in the province of Ontario, Dominion of Canada, have jointly invented certain new and useful Improvements in Relief-Valves for Engines, of which the following is a specification.

10 The object of the invention is to provide a main valve for steam and other engines which will admit the steam into the cylinder without any retarding pressure on itself, and in which provision is made to relieve the engine-piston 15 from back-pressure caused by the engine pumping air when running light; and it consists in a double-ended piston-shaped valve adapted to work within an open-ended cylindrical chamber formed within the main steam-chest, 20 and provided with suitable steam inlet and exhaust ports, an auxiliary relief-valve being applied thereto, as hereinafter more particularly explained.

Figure 1 is a sectional view of an engine-25 cylinder provided with our improved balanced valves. Fig. 2 is a detail view of the valves.

In the drawings, A is the steam-cylinder, which, with the piston-head and piston-rod, is of substantially the usual construction.

30 C are two pistons mounted upon a spindle, C', and forming a double-ended piston-shaped valve placed within a cylindrical chamber formed within the steam-chest.

E are the steam-inlet ports to the cylinder 35 from the valve-chamber, and F is the exhaust-port.

As both ends of the cylindrical casing G are open, the pressure of steam is equal and continuous at each end of the valve, and as the 40 casing G protects the circumference of the valve from pressure it is therefore perfectly balanced and will perform its duty without appreciable friction.

The operation of the valve is so clearly shown 45 by the drawings that it is unnecessary to describe it further than to say that as the valve is moved to and fro steam is alternately admitted to and exhausted from the cylinder, and the valve, being, as before stated, perfectly balanced, moves with but little friction, and therefore with great economy of power.

When our improved valve is applied to a locomotive we make the following provision to

5 prevent the back-pressure caused by the engine pumping air when the steam is cut off and the engine running free downgrade. The said provision consists of an automatic safety relief-valve, H, placed in a chamber formed in the top of the steam-chest, which chamber is connected by the pipes I to the steam-ports E, 60 connecting the steam-chest and cylinder.

J is a spiral spring placed below the valve H for the purpose of holding it against its seat, closing the connection between the interior of the steam-chest and the two pipes I I', 65 the steam-pressure within the steam-chest imparting the pressure necessary to insure a steam-tight joint. When the steam is cut off from the steam-chest the automatic relief-valve H may be easily pressed clear of its seat, 70 as the spiral spring J is designed merely to support the weight of the valve. When the engine is running without steam the air within the cylinder is compressed by the movement of the piston, having no exit through 75 the ports E from the point where the steam is cut off till it commences to exhaust. The back-pressure thus produced injuriously affects the working of the engine unless means are provided to permit the escape of the air being 80 compressed.

When our automatic relief-valve is applied the air is forced by the piston up through the pipe I till it reaches the valve H, and, the pressure of the air thus forced being sufficient 85 to push the valve H clear of its seat, the air is permitted to continue its passage down through the other pipe, I', till it reaches the port E leading to the cylinder at the opposite end of the piston, where a partial vacuum has been 90 formed by the movement of the piston.

What we claim as our invention is—

1. In a relief-valve, and in combination with the valve-chamber having a relief-chamber and port-connections with the main cylinder, a series of pipes connecting such ports and relief-chamber, and a spring-valve operating in such chamber, as and for the purpose set forth. 95

2. In a steam-chest having pipe-connections I I' with the ports E, the relief-valve H and spring J, as set forth.

JAS. LIVINGSTON.
J. KENNEDY.
